UNITED STATES PATENT OFFICE.

JOSEPH C. BRUNO, OF BUFFALO, NEW YORK, ASSIGNOR, BY MESNE ASSIGNMENTS, TO
JOHN L. OSGOOD, OF BUFFALO, NEW YORK.

CAN-FILLING MACHINE.

Application filed January 23, 1922. Serial No. 531,067.

To all whom it may concern:

Be it known that I, JOSEPH C. BRUNO, a citizen of the United States, residing at Buffalo, in the county of Erie and State 5 of New York, have invented certain new and useful Improvements in Can-Filling Machines, of which the following is a specification.

My invention relates to improvements in 10 can-filling machines, and more particularly to that type of machine in which cans are filled according to weight, each can receiving a predetermined weight of material.

One of the objects of my invention is the 15 provision of an improved can-filling machine which is positive in action and highly sensitive so that when the material being filled into a can or other receptacle reaches the predetermined weight, the flow of the 20 material will be mechanically shut-off without variation in weight in the various cans filled.

Another object of my invention is to provide a can-filling device of this kind from 25 which the discharge of the material with which cans or other receptacles are to be filled may be controlled either by hand or foot manipulation.

A further object of my invention is the 30 provision of a machine of this kind of comparatively few parts, and which can be easily cleaned to remove any material adhering to the internal surfaces of the walls forming the conduits, chambers, or passages 35 through which the material is passed.

With the above-mentioned and other objects in view, the invention consists in the novel features of construction, and in the arrangement and combination of parts and 40 devices to be hereinafter described and more particularly pointed out in the subjoined claims.

In the drawings:—

Fig. 1 is a front elevation of the machine.

Fig. 2 is an end view of the same.

Fig. 3 is an enlarged front elevation of 45 part of the controlling mechanism, showing part of the operating handle broken away and showing a portion of the operating rod forming part of the foot operating mechanism.

Fig. 4 is an enlarged substantially horizontal section taken on line 4—4, Fig. 3.

Fig. 5 is an enlarged horizontal section 55 taken on line 5—5, Fig. 2.

Fig. 6 is a detached perspective view of the adjustable scale platform.

Fig. 7 is an enlarged vertical section taken on line 7—7, Fig. 1.

Fig. 8 is a perspective view of the combined guide and stop member and adjacent parts. 60

Fig. 9 is an enlarged cross section taken on line 9—9, Fig. 3.

Fig. 10 is a cross section taken on line 65 10—10, Fig. 4.

Fig. 11 is an enlarged vertical section taken on line 11—11, Fig. 2.

Fig. 12 is a horizontal section taken on 70 line 12—12, Fig. 1.

Fig. 13 is a detached perspective view of a part of the trip lever.

Fig. 14 is a detached perspective view of the supporting bracket provided for the trip lever and other movable parts of the device. 75

Fig. 15 is an enlarged vertical section taken on line 15—15, Fig. 25.

Fig. 16 is a detached perspective view of 80 the scale frame.

Fig. 17 is an enlarged vertical section taken on line 17—17, Fig. 12, looking toward the left.

Fig. 18 is a vertical section taken on line 85 18—18, Fig. 19.

Fig. 19 is a front elevation of a portion of the scale.

Fig. 20 is a vertical section taken on line 90 20—20, Fig. 1, looking toward the left.

Fig. 21 is a vertical section through the 95 inlet valve of the liquid storage tank and adjacent parts directly connected therewith.

Fig. 22 is a detached perspective view of the detent arm.

Fig. 23 is a detached perspective view of 100 the lower end portion of the valve rod within the liquid storage tank.

Fig. 24 is an enlarged vertical section taken on line 24—24, Fig. 25.

Fig. 25 is a central vertical section 105 through a portion of the liquid storage tank.

Reference being now had to the drawings in detail, like numerals refer to like parts in the several figures.

The reference numeral 26 designates the 110 main support or frame of the machine, which comprises a base 27 cast to any desired form and of sufficient area to provide a solid foundation for all parts of the machine carried by the upright 28 of said 115

support or frame. The base is formed with an upstanding socket 29 into which the lower end of the upright 28 is seated, and this upright preferably has its lower portion cylindrical, as at 30, and its upper portion square, as at 31.

While I have shown and prefer a solid upright with a cylindrical lower portion and a non-cylindrical upper portion on account of certain advantages gained thereby, it is to be understood that the upright may be formed hollow and if desired be differently shaped.

Projecting forward from the cylindrical portion of the upright 28 is what I term a scale-supporting bracket 32 and projecting forward from the square or non-cylindrical portion of said upright is what I term a valve-supporting bracket 33. Each of these brackets comprises two exact counterparts 34, each provided near each end with a transverse depression 35 on its inner surface, the depression in the scale-supporting bracket being semi-circular while those in the valve-supporting bracket are V-shaped. The two counterparts or members of the scale-supporting bracket are positioned at opposite sides of the cylindrical portion of the upright 28 with said upright entering both semi-circular depressions at the inner end of the bracket, and passing through the inner extremities of the two counterparts or members 34 of said bracket is a clamping bolt 36.

35 A stud 37 depending from a scale frame 38 is fastened in the outer end of the scale-supporting bracket 32, the two semi-circular depressions at the outer ends of the two members 34 thereof forming a circular opening to receive said stud, and a clamping bolt 39 is passed through the outer extremities of said members and thus clamps the scale frame in said bracket. By securely tightening the nuts of the clamping bolts 36 and 39, the scale-supporting bracket will be securely fastened to the upright 28 and the scale frame will be firmly clamped in position within said bracket.

50 The scale frame comprises a longitudinal member 40 and a transverse member 41 mid-length thereof, said transverse member extending from opposite sides of the longitudinal member and having upstanding lugs 42 provided with V-shaped depressions 43 55 in their upper faces. This scale frame is preferably cast and at the points of said depressions has steel or other hardened inserts 44 into which the pointed inner ends of the depressions extend. As a convenient 60 means of providing hardened bearing points at the inner ends of said depressions, circular openings are bored through the upstanding lugs 42 and into these openings steel plugs are inserted, the ends of said 65 plugs being flush with the outer and inner

surfaces of said lugs. The V-shaped depressions are then machined into the lugs with the pointed lower ends of the depressions formed in said steel plugs. At the outer extremities of the longitudinal member of 70 said scale frame, vertical openings 45 are formed into which supporting rods 46 are fastened by means of set screws 47 which are threaded through the ends of said longitudinal member and bear against said rod. The lower ends of said supporting rods are provided or formed with enlargements 48 which rest upon the base 27 of the support or frame or upon the floor. Thus the 75 scale frame is supported at its ends and centrally between its ends.

49 designates the scale beam which has a central transverse member 50 and end members 51, 52, connected with said central transverse member by arms 53. Passing 80 transversely through said central transverse member and fastened therein by a set screw 54 is a fulcrum member 55 having opposite ends provided with downwardly directed V-shaped portions 56 forming knife edges 90 which bear against the hardened plugs or inserts 44 of the upstanding lugs 42. Each of the end members 51, 52 has a fulcrum member 57 fastened therein, and opposite 95 ends of each of these members is provided with upwardly-directed V-shaped portions 58 forming knife-edge fulcrum points.

59 designates a platform frame which comprises a hub portion 60 and four diagonally-disposed or radial arms 61 extending outwardly from said hub portion. The outer end of each of these arms is provided with a vertical opening and through these openings, platform supporting rods 62 depending from a can-supporting platform 63 are 100 passed, said rods 62 being adjustable within said openings and being held in any adjusted position by means of set screws 64.

Extending outwardly from the hub portion 60 of the platform frame and connecting the diagonally-disposed arms 61 in pairs are two bearing members 65 provided on their under sides with V-shaped depressions 66 extending into steel or other hardened inserts 67, which are similar in form and applied in the same manner as the steel inserts 44 in the scale frame. The upwardly directed V-shaped portions 58 of the fulcrum member 57 serve as fulcrums for said platform frame, the knife edge bearings of 110 said fulcrum member being in contact with the pointed inner ends of said V-shaped depressions.

A U-shaped casting 68 is secured to the under side of the platform frame 59 and 115 may be said to form part thereof. This casting has ears 69 through which bolts 70 are passed that take into the under side of the hub portion 60 of said platform frame. The vertical members of the U-shaped por- 120

- tions are provided with notches 71 into which the ends of the fulcrum members 57 extend, the walls of said notches being, however, out of contact with said fulcrum member so that the platform frame and the supported platform are carried solely by the knife edged portions of the fulcrum member 57.
- Threaded into the U-shaped casting 68 is a rod 72 which has a nut 73 applied thereto bearing against the under side of said casting. This rod may be adjusted within the casting and retained in any adjusted position by said nut.
- 15 74 designates a weight table having a central depending boss 75 into which is threaded a screw stud 76 projecting upwardly from a cavity 77 formed in a table support 78 having depending lugs 79 provided on their under sides with V-shaped depressions 80 extending into steel or other hardened inserts 81 which are also similar in form and applied in the same manner as the steel inserts 44 in the scale frame. A U-shaped casting 82 is secured to the under side of the table support 78 and may be said to form part thereof. This casting has ears 83 through which bolts 84 are passed that take into the under side of the table support. The vertical members of the U-shaped casting 82 are provided at their upper ends with notches 85 into which the ends of the co-operating fulcrum member 57 extend. Like the walls of the notches 71, the walls 35 of these notches are also out of contact with said fulcrum member so that the table support, like the platform support, is carried solely by the knife edge portion of the fulcrum member.
- 40 Threaded into the U-shaped casting 82 is a rod 86 which has a nut 87 applied thereto, said nut bearing against the under side of said casting. The rod 86 is therefore adjustable within the casting and may be retained in any adjusted position by said nut.
- The scale frame 38 is provided at opposite ends and adjacent the vertical openings 45 with comparatively large openings 88 through which the rods 72 and 86 are 50 passed, the lower ends of said rods being bifurcated, as at 89, to receive the ends of a balance lever 90, said ends being pivotally secured within the bifurcated ends of said rod and said balance lever being pivotally 55 fastened within the lower end of the stud 37 of the scale frame 38, as at 91. The weight table 74 is easily removable from the table support 78, as it is simply necessary to unscrew the same from the screw stud 60 76. This will permit shot 92 or other fine balancing material to be placed within the cavity 77 of the table support and thus assure exact balance of the scale beam.
- To prevent accidental removal of the 65 scale frame from its bearings, angle-shaped
- retainers 93 are fastened to the outer side of the upstanding lugs 42 at opposite ends of the transverse member 41 of the scale frame.
- Secured within the outer end of the valve 79 supporting bracket 33 is a square stud 94 depending from a combined valve and mechanism casing 95 and a short distance above the valve supporting bracket is a third bracket 96 which extends rearwardly 75 from the support 26. The bracket 96 supports a float-controlled tank 97 having an inlet pipe 98 through which is passed the liquid to be filled into cans or other containers from said tank, this liquid being supplied from a suitable storage tank (not shown) preferably arranged in a higher plane than the tank 97 so that the liquid will be fed into said tank 97 by gravity.
- Connecting the combined valve and mechanism casing 95 with the float-controlled tank 97 is a supply pipe 99 which includes a flanged coupling or other suitable fitting 100 riveted or otherwise secured to the bottom of the wall of the tank 97, as at 101, and into which said supply pipe is threaded. Arranged in this supply pipe is a union 102 by means of which the casing 95 can be conveniently disconnected from the tank 97 when it is desired to clean said casing. The supply pipe 99 is provided with a hand valve 103 whereby the flow of the liquid from the float-controlled tank may be shut off.
- As clearly shown in Figs. 21 and 25, the float-controlled tank 97 has its inlet pipe 98 connected to one of the walls thereof by a flange fitting 104 which is riveted or otherwise fastened to said wall, and threaded into said fitting from the interior of the tank is a valve fitting 105 which comprises a cylindrical open-ended member 106 externally threaded along a portion of its length for entrance into the flange coupling 104 and being provided adjacent said externally-threaded portion with a hexagonal or other wrench-applying enlargement 107 by means of which the valve fitting may be securely fastened in place. Said cylindrical open-ended member has a raised valve seat 108 at its inner end and the hexagonal enlargement 107 is provided with an inwardly-directed arm 109 having an upstanding terminal 110 to which a valve-controlling lever 111 is pivotally secured, said lever having an upwardly and outwardly-curved projection or toe 112 at its pivoted end which bears against a flat valve 113 pivotally secured to the arm 109, as at 114, said valve having a fiber or other facing 115 adapted to bear against the raised valve seat 108. The outer end of said lever is pivotally secured to the lower end of a link 116 having pivotal connection at its upper end with a float 117, said float being

- a hollow box-like member formed of metal and provided centrally with a tube 118 which extends through said box-like member and projects both upwardly above the 5 upper wall of said member and downwardly below the lower wall thereof, said tube being securely soldered or otherwise secured to said box-like member to render the interior of said member air-tight.
- 10 Extending transversely through the upper projecting end of the tube 118 are small tubes 119 which are alined and soldered or otherwise fastened at their outer ends in openings formed in said tube 118, as best 15 shown in Fig. 15. The alined tubes 119 are separated at their inner ends and between the same the upper end of the link 116 is adapted to be positioned, said link having a plurality of spaced pivot holes 120, any one 20 of which is adapted to be brought into registration with said small tubes. Through said tubes 119 and the registering pivot hole of said link, a pivot pin 121 is passed, said pin projecting beyond the outer ends of said 25 tubes 119 and having cotter pins 122 passed therethrough to hold the parts in position. The float is therefore adjustable on the link 116, as it is simply necessary, in order to adjust the same, to remove the pivot pin 121 30 and lower or raise the float, as the case may be, to bring a different pivot hole in the link 116 into registration with the small alined tubes 119. These tubes provide extended bearings for the pivot pin 121 and 35 also maintain the link 116 in outward position. For convenience in adjusting the float on the link I have provided means for retaining the link in vertical position, and for this purpose have riveted to opposite sides of the 40 link, flat springs 123, which normally have their free lower ends curved outwardly, and said free lower ends are provided with pivot holes 124 which register with a pivot hole 125 in the link 116. The lower end of said link 45 with the springs pressed inwardly against the same are inserted within the bifurcated portion of a coupling or other fitting 126 secured to the outer end of the valve controlling lever 111, a pivot pin 127 being passed 50 through said fitting and through the springs and link. The springs tend to exert pressure outwardly against the inner surfaces of the bifurcated portion of said fitting and thus retain the link in any position it may be 55 placed, yet allow free action of the lever when the float secured to the upper end of the link rises or lowers. For convenience in adjusting the float on the link, the upper end of the float-controlled tank 97 is open and 60 therefore access may be easily had to the pivot by means of which the float is connected to the link. In order to prevent dust and dirt entering the float-controlled chamber, the upper open end thereof is closed with 65 a cover 128.
- When starting the machine in operation, the weight of the float will cause it to lower, with the result that the valve 113 will be open. Now, when feeding liquid into the float-controlled chamber, the level thereof 70 will gradually rise until it reaches a height sufficient to support the float, whereupon said float will gradually rise with the rising liquid, and when it reaches a predetermined high level in accordance with the adjustment 75 of the float on the link 116, the flat valve 113 will close against the valve seat 108, thereby shutting off the flow of liquid into said tank. It is, however, apparent that the liquid is free to flow into the combined valve and 80 mechanism casing 95, except when the hand valve 103 is closed. The discharge of liquid from the combined valve and mechanism casing will be controlled by mechanism to be presently described. 85
- When the level of the liquid within said tank lowers, the float will descend and cause the valve-controlling lever 111 to swing on its pivot, with the result that the flat valve 113 will swing into open position, by reason 90 of the pressure of the liquid behind the valve overcoming that of the liquid within the tank, the open position of the valve being indicated by dotted lines in Fig. 21.
- The float-controlled tank 97, as stated, is 95 supported by the upright 28, but as the point of attachment of said tank to said upright is at the front of the tank, I provide additional supports 129 at each side, these additional supports being in the form of upright 100 bars secured at their lower ends to upstanding lugs 130 on the base 27 and passing through loops 131 on the bracket 96, said loops having set screws 132 by means of which the float-controlled tank 97 may be secured at any desired point along said additional supports. In this manner the weight 105 of the float-controlled tank and its contents is not solely supported by the upright 28, which would cause a slight bending of said 110 upright and consequently create more or less binding of certain of the moving parts of the machine. 110
- The combined valve and mechanism casing 95 has a horizontal conduit 133, to one end 115 of which the supply pipe 99 is connected, the other end of said horizontal conduit opening into a vertical conduit 134 projecting a short distance beneath said horizontal conduit, as at 135, and a considerable distance 120 thereabove, as at 136. The upper end of said vertical conduit is closed, while the lower end thereof is open and internally threaded. The square stud 94, hereinbefore referred to, is preferably arranged at the inlet end of 125 the casing 95, as best shown in Fig. 11, and at said end the horizontal conduit 133 is substantially spherical in formation with an opening 137 at one side thereof which is internally threaded to receive a shaft bearing 130

138 forming part of a stuffing box 139. In said shaft bearing, a rock shaft 140 is arranged for rocking movement, said rock shaft extending inwardly into the spherical portion of said horizontal conduit and outwardly through said stuffing box. Said rock shaft 140 is provided with an annular groove 141 into which the end of a set screw 142 is entered, said set screw being passed through 10 the wall of said shaft bearing and permitting rocking movement of said shaft within its bearing but preventing lengthwise movement thereof.

Fastened to the inner end of the rock shaft 140 within said horizontal conduit is one end of a valve-actuating lever 143 terminating at its other end within the vertical conduit 134 in the form of a hook 144. Threaded into the lower end of the vertical 20 conduit 134 is a combined nozzle and valve-seat 145, the exterior of which has a polygonal flange 146 formed thereon so that it can be easily removed and replaced with another of smaller or larger size, as may be 25 found desirable. The portion of said nozzle below said flange is adapted to be shaped to conveniently enter the filling openings of the cans to be filled, depending more or less on the size of the opening within the can 30 and in some cases on the formation of said opening.

For purposes of illustration I have shown a can in dotted lines in Fig. 1, as at 147, but in this instance the lower end of the nozzle 35 terminates above the filling opening of the can, as such a position may be found desirable when filling cans with certain kinds of material.

The interior diameter of the nozzle at its 40 lower end is of a size that it will feed into the cans to be filled without any portion of the liquid coming in contact with the tops of the can or other receptacle.

Within the vertical conduit 134, with 45 which may be included the interior of the combined nozzle and valve seat 145, is a shut-off or flow-controlling valve 148 adapted for vertical movement, said valve being shaped to conform to the interior of the 50 nozzle so that when seated against the inner surface of the nozzle it will effectually close the same and prevent feeding of the liquid therethrough. This valve is provided with a socket 149 at its upper end into which is 55 loosely fitted the lower end of a stud 150, said stud being pivotally secured within said socket by a pivot pin 151 so that the valve will be able to adjust itself to its seat within said nozzle. The upper end of 60 said stud is threaded into a loop 152 which has the lower end of a rod 153 threaded into its upper end, said rod extending upwardly into the vertical conduit 134 and having a weight 154 secured thereto. That portion 65 of the vertical conduit extending upwardly

above the horizontal conduit may be termed an air chamber and in this air chamber the weight 154 and rod 153 are positioned.

The inner walls of the loop 152 are rounded, as at 155, and into the opening of said 70 loop the hook end 144 of the valve actuating lever 143 is positioned.

Controlling mechanism is arranged between the outer end of the rock shaft 140 and the weight table 74 of the scale, and for 75 the purpose of properly supporting this controlling mechanism I secure a hanger 156 to the shaft-bearing 138, which bearing may be said to form part of the combined valve and mechanism casing 95. This hanger 80 comprises a hub 157 which has an axial opening 158 therein and a pair of spaced lugs 159 extending upwardly therefrom; said hub being split from said opening outwardly to the space between said lugs so as 85 to form a contractable hub and for this purpose a clamping bolt 160 is passed through one of said lugs and threaded into the other. This arrangement permits the hanger 156 to be adjusted lengthwise on the shaft bearing 90 138.

Projecting from said hub 157 are two arms 161, 162 arranged in diverging lines. These arms have at their outer or lower 95 ends, laterally-extending bosses 163, 164, respectively.

Secured to the top of the combined valve and mechanism casing 95 is a combined 100 guide and stop member 165, which projects forwardly, and at its front end has a guide boss 166 through which a vertically-movable operating rod 167 is passed, said rod forming part of foot-operating mechanism and having a lifter or actuating member 168 adjustable thereon. The lower end of said 105 rod passes through a guide bracket 169 secured to the base 27 and at said lower end is threaded into a forked fitting 170 pivotally connected to the inner end of a foot lever 171, said foot lever being pivotally 110 secured at a point between its ends between upstanding lugs 172 and having a treadle 173 at its outer end. Between the forked fitting 170 and the portion of the guide bracket 169 through which said operating 115 rod 167 passes, a spiral spring 174 is arranged, said spring surrounding said rod and bearing with its upper end against said guide bracket and with its lower end against said fitting to keep the inner end of said foot lever 171 depressed and the operating rod 167 lowered.

The lifter or actuator member 168 comprises a body portion 175 having a vertical 125 opening through which the operating rod 167 is passed, said body portion being split from said opening to one end of said body portion, and through this split part a clamping bolt 176 is passed which serves to fasten the lifter or actuator member firmly to said 130

rod at any point desired. Fastened to said body portion 175 is an upwardly-swinging trip dog 177 having an upwardly-and-outwardly inclined surface 178 and a substantially flat horizontal surface 179 against which one end of a spring 180 bears, which spring is secured to the body portion of said lifter or actuator member, as at 181, and serves to retain said dog in its lowered position.

Fastened to the outer end of the rock shaft 140 is a detent arm 182, from which a hand operating lever 183 extends, said lever extending from said arm at a point adjacent the attachment of said arm to said rock shaft. Said hand operating lever 183 has an outwardly-extending trip stud 184 adjustably secured thereto, and for this purpose said lever is provided with a longitudinal slot 185 in which said stud is movably secured in any approved manner. The outer or actuating end of said trip stud is substantially V-shape in cross section, with the edge or point thereof directed toward said detent arm. The spring-retained trip dog 177 is adapted to engage the under side of the trip stud 184 when the operating rod 167 is elevated by the foot lever 171. This trip dog is adapted to elevate the hand operating lever 183 and after elevating the same to a certain angle, namely that shown in full lines in Fig. 3, said trip dog is adapted to pass beyond and above said trip stud.

When releasing the foot lever 171, the spiral spring 174 causes the operating rod 167 to lower, whereupon the upwardly-and-outwardly inclined or beveled surface 178 of the trip dog will engage the upper inclined face of the trip stud 184 and be swung on its pivot so that it will pass idly over the pointed edge of said trip stud and beneath the same without in any manner effecting the hand operating lever 183.

It is apparent therefore from the foregoing, that the mechanism may be actuated either by hand or by foot, and that the foot operating mechanism causes operation of the machine through the medium of the hand operating lever 183; the parts, however, being so arranged that said hand operating lever may be operated without causing movement of the foot operating mechanism, or any part thereof.

The combined guide and stop member 165 is provided with an adjustable stop bolt 186 which is threaded upwardly through the outer end of said guide and stop member at one side of the guide boss 166 thereof and retained in any adjusted position by means of a jamb nut 187, which is threaded onto said bolt and bears against the under side of said guide and stop member. The head of said bolt 186 is adapted to be engaged by the hand operating lever 183 and limits the upward movement thereof, and in order that

the spring-pressed trip dog 177 will pass upwardly beyond the trip stud 184 at the instant that the hand operating lever engages the stop bolt 186, said bolt is adjusted to the exact point allowing such action by moving it along the longitudinal slot 185.

The detent arm 182 is provided at its lower end with an elongated detent shoe 188 having a hardened contact portion 189 on its under side at one end thereof. 190 75 designates a supporting member formed of sheet metal and having a vertically-disposed portion 191 and a horizontally-disposed portion 192 extending forwardly from the lower edge of said vertically-disposed portion, said vertically-disposed portion having a forwardly-extending stop lug 193 thereon and at opposite ends it is provided with bolt holes 194, 195. Through the bolt hole 194 a bolt 196 is passed, which is 80 threaded into the boss 163, thus securely fastening one end of said supporting member to the hanger 156. A bolt 197 is threaded into the other boss 164 and surrounding it is a spacing sleeve 198, said bolt 197 having an inwardly-facing shoulder 199 which bears against the outer end of said spacing sleeve, while the inner end thereof bears against the outer face of the vertically-disposed portion 191 of the supporting member 190.

200 designates a detent lever pivotally secured at one end by said bolt 197, said lever being retained in position on the enlarged portion of said bolt between the outer end of said spacing sleeve 198 and the head of said bolt. Said detent lever extends from its pivotal point directly over the horizontally-disposed portion 192 of the supporting member 190 and is held in elevated position 10 by a spring 201 secured with one end to said horizontally-disposed portion and bearing with its other or free end against the under side of said lever.

The detent lever comprises what may be 11 termed a hub portion 202, which is provided with a threaded bore 203 into which one end of a lengthening rod 204 is threaded, said rod having its other end threaded into the outer or main portion 205 of said lever. 11 Bearing against what I have termed the hub portion of the lever is a detent plate 206, which has an upwardly projecting portion and which is held against said hub portion by a nut 207 threaded onto the 12 lengthening rod 204, said detent plate having a beveled edge 208 and the upwardly projecting portion thereof being adapted to engage the hardened contact portion 189 of the detent shoe 188.

Fastened in a bolt hole 209 in the vertically-disposed portion 191 of the supporting member 190 is a pivot bolt 210, which has a reduced threaded end providing a shoulder adapted to bear against the outer 13

side of said vertically-disposed portion 191, while a nut is threaded onto said reduced portion and bears against the inner side of said vertically-disposed portion 191 so as to 5 firmly secure said bolt in place. Between the head of said bolt and a washer 211 which surrounds said bolt and bears against the outer side of said vertically-disposed portion 191 is arranged for swinging movement 10 a trip lever 212, which is partly in the form of a bar 213 of rectangular formation and partly in the form of a rod 214 which is threaded into said bar and extends laterally therefrom. The rod portion of said trip lever is in contact with the saddle-like bearing member 215 of a vertically-disposed trip rod 216. Said trip rod is adjustably secured to the table support 78 of the scale, as at 217 so that it may be adjusted vertically 15 to assure proper actuation of the trip lever 212.

The trip lever has the pivot bolt 210 passed through its rectangular portion near the secured end of the rod 214 forming part thereof and it is closer to one end than the other so that the trip lever may be said to have a short arm and a long arm.

It is to be noted that the outer end of the 20 detent lever 200 is provided with an adjustable bolt 218, the head of which is provided with a rounded contact portion 219, which bears against the under side of a contact plate or arm 220 extending forwardly from the short arm of said trip lever. Said bolt is adjustably threaded through the 25 detent lever 200 and has a nut 221 threaded thereon which bears against the under side of said detent lever and retains the bolt at the desired adjustment. The upward movement 30 of the trip rod 216 is therefore imparted to the detent lever 200 through the medium of the trip lever 212, causing said detent lever to be depressed against the action of the spring 201. When, therefore, the 35 detent lever is depressed the pointed upper end of the detent plate 206 will become disengaged from the detent shoe 188, which will permit the shut-off or flow-controlling valve 148 to close against its seat within the nozzle 145, due to the fact that the weight 154 within the air chamber of the casing 95 will 40 act to depress the valve-actuating lever 143 and cause the rock shaft 140 to rock; said shaft in turn swinging the detent arm 182 to the right in Fig. 1, such action of said arm being assured by reason of the fact that on 45 the hand operating lever 183 a weight 222 is adjustably held, said weight being movable toward and from the detent arm and 50 being retained in any adjusted position by a set screw 223, or otherwise. The degree of contact or bite which the detent plate 206 takes against the detent shoe may be governed to a nicety by adjusting the bolt 218.

By means of the provision made for shortening or lengthening the detent lever, and by reason of the adjustment of the bolt 218 in said lever, a very sensitive action is secured between the detent arm, and more particularly the shoe thereof, and the detent 70 lever when the trip lever is actuated by the trip rod 216 and assurance is had that every can being filled will have the exact weight of all other cans filled with the same material.

The hand operating lever 183 bears against the adjustable stop bolt 186 when in elevated position, which bolt limits the opening movement of the shut-off or flow-controlling valve 148, and also limits the 80 range of movement of the detent arm 182 in one direction. With a supply of liquid stored in the float-controlled tank 97 the liquid is passed through the combined valve and mechanism casing 95 of the machine 85 and when the level of the liquid lowers within the tank 97 the valve 113 therein will open and admit an additional quantity of liquid to said tank from the inlet pipe 98 until the proper level within the tank is 90 again reached, which causes said valve to be closed by the float 117 and parts between the same and said valve. In this manner the liquid is maintained at a constant level in the float-controlled tank 97 and the pressure of the liquid passing through the combined valve and mechanism casing 95 is constant at all times. When the shut-off or flow-controlling valve 148 is in closed position within the nozzle 145, the flow of the 100 liquid is stopped. When, however, the machine is not in use the hand valve 103 is closed. When the hand valve 103 is opened and the shut-off or flow-controlling valve 148 is closed, the machine is in condition 105 for operation.

The operation of the device is as follows:

A can or other receptacle to be filled is placed upon the platform 63 of the scale, this platform having been previously adjusted vertically to bring the filling opening of the can or receptacle thereon directly underneath and in close proximity to the discharge opening of the nozzle 145. Assuming the can to hold a pound of liquid when 110 filled, a one pound weight is placed upon the weight table 74 of the scale, with the shut-off or flow-controlling valve 148 closed against its seat within the nozzle 145, the hand operating lever 183 is in the position 115 shown in dotted lines in Fig. 3, the detent arm 182 with its shoe, the detent lever 200, and the trip lever 212 being also in the positions shown in dotted lines in said figure. When a can or other receptacle is placed on 120 the platform 63 of the scale and a proper counterweight placed upon the weight table 74, the hand operating lever 183 is 125 swung

upwardly by grasping the outer end of the same or by actuating the same through the medium of the foot lever 171. This will cause the detent arm 182 to swing 5 from the position shown in dotted lines in Fig. 3 to that shown in full lines so as to bring the outer end of the shoe thereof in contact with the detent plate 206, thereby retaining said hand operating 10 lever and detent arm in the position shown in full lines in Fig. 3. Due to the detent arm being secured to the rock shaft 140, the valve actuating lever 143 within the casing 95 will be elevated from the position shown 15 in full lines, thereby elevating the weight 154 and unseating the shut-off or flow-controlling valve 148 so that a free escape for the liquid is provided through the nozzle 145. The liquid thereupon enters the can 20 or receptacle placed upon the platform 63 of the scale and the weight thereof gradually depresses said platform and elevates the weight table 74 with the counterweight thereon, thereby causing the trip rod 216 to 25 be elevated, which in turn swings the trip lever 212 on its pivot and causes depression of the short arm of said trip lever, the contact plate or arm 220 on said trip lever being at all times in contact with the adjustable bolt 218, therefore causing depression 30 of the detent lever 200 so as to disengage the detent plate 206 thereof from the end of the detent shoe 188 at the lower end of the detent arm 182. This action releases the rock 35 shaft 140 and the weight 154 surmounting the shut-off or flow-controlling valve 148 and causes said valve and the valve actuating lever 143 connected with said valve to be depressed, thereby shutting off all liquid 40 from the platform.

In order to position the cans or other receptacles to be filled in proper position underneath the nozzle 145, a can or receptacle 45 guide-device is provided. This is formed of a piece of wire or rod material doubled midlength upon itself, as at 224, Fig. 6, to provide two parallel spaced parts 225, which have their outer ends inclined outwardly, as at 226, thus forming a flaring 50 guide for the cans or receptacles. This guide is placed upon the can-receiving platform 63, which is provided with a number of openings 227 arranged along one or more marginal portions thereof. A thumb screw 55 228 acts against the parallel parts 225, either directly or through a retainer piece, and is threaded into any one of the openings 227, said thumb screw passing downwardly between said parallel parts and clamping 60 the same in any position. With the thumb screw passed between the parallel parts and loosened, the guide device is free to be swung into any position, using said thumb screw as a pivot or fulcrum point, or it may

be moved inwardly along a straight line so 65 as to bring the thumb screw closer to the flaring guide portion of the device, or farther from the same, as may be desired.

An arrangement such as described permits 70 adjustment of the guide device laterally or longitudinally, or an adjustment may be effected in which a combination of both lateral and longitudinal movement is included. Moreover, the flaring guide portion of the 75 device may be positioned at any point on the platform, due to the provision made for securing the guide member at different points on the platform. Thus, a receptacle either square, round, or oval of any cross-sectional 80 measurements may be positioned directly under the nozzle 145 of the machine so that said nozzle will fit into or be positioned directly over the filling opening of the receptacle, regardless of the position on the can of said filling opening. After once adjusting 85 the guide to the filling opening of any can, all cans of the same size and shape can be quickly placed upon the platform and guide to position by moving them against the flaring members 226 of the guide with 90 absolute assurance that the filling opening will be directly underneath the nozzle and no loss of material result from the operation of the machine.

The detent mechanism may be referred to 95 as holding or latching means, since it holds and latches the shut-off or flow-controlling valve and associated parts in open positions.

In its broadest sense, certain parts of my 100 improved machine may be said to constitute controlling mechanism, such mechanism including trip mechanism, detent mechanism, and parts between said detent mechanism and the shut-off or flow-controlling valve 105 148. The term "operating mechanism" is when disassociated from the word "foot" is intended to mean all parts between the hand operating lever 183 and the shut-off or flow-controlling valve 148 or their equivalent, 110 either with said hand operating lever or with foot operating mechanism, or both with hand and foot operating mechanisms, and the term "hand operating mechanism" 115 in the claims hereto is intended to mean the hand operating lever 183 and parts connecting said lever with the shut-off or flow-controlling valve 148.

Having thus described my invention, what I claim is:—

1. In a can-filling machine, the combination 120 of a supported scale, a supported casing in a plane above said scale having a liquid inlet and a liquid outlet, a normally closed valve for said liquid outlet, operating mechanism for opening said valve, trip mechanism connected to said operating mechanism and having connection with said scale, and detent mechanism comprising two movable

parts, one of said parts being connected with said operating mechanism and the other being adjustable with respect to said first-mentioned part and having a portion engaging said first-mentioned part to retain said operating mechanism in actuated position, said engaging portion being spring-retained, said trip mechanism being adapted to release one of the parts of said detent mechanism from the other part thereof and permit closing of said valve and being actuated by said scale.

2. In a can-filling machine, the combination of a casing having a liquid inlet and a liquid outlet, a normally closed valve for said liquid outlet, a bracket supported to said casing and having a pair of diverging arms provided at their outer ends with outstanding bosses, and controlling mechanism having a part thereof pivotally secured to the boss of one of said arms and a part thereof pivotally supported a distance from the pivot of said first-mentioned part.

3. In a can-filling machine, the combination with a scale, of a casing having a liquid inlet and a liquid outlet, a valve normally closing said liquid outlet, hand operating mechanism including a hand lever for opening said valve, a bracket secured to said casing and provided with a guide opening, foot operating mechanism including a vertically movable rod guided in said guide opening and adapted for co-action with said hand operating lever, detent mechanism co-acting with said hand operating mechanism to keep said valve open, and trip mechanism actuated by said scale and adapted for co-action with said detent mechanism.

4. In a can-filling machine, the combination with a casing having a liquid inlet and a liquid outlet, of a normally closed valve for said liquid outlet, operating mechanism for opening said valve including a hand lever having a trip stud, foot operating mechanism including a vertically movable rod and a trip dog on said rod adapted to engage said trip stud to cause actuation of said hand lever in one direction, said trip dog riding idly over said hand lever upon the return movement of said rod.

5. In a can-filling machine, the combination of a casing having a liquid inlet and a liquid outlet, a valve for closing said liquid outlet, mechanism for opening said valve including a hand operating lever having an outstanding trip stud, foot operating mechanism including a vertically movable rod having a trip device adjustable thereon including a spring-pressed pivotally secured trip dog, said trip dog being adapted to engage said trip stud to cause movement of said hand operating lever in one direction and being adapted to ride idly over said trip stud upon the return movement of said rod.

6. In a can-filling machine, the combination with a scale, of a casing having a normally closed valve controlling the discharge of liquid therefrom, a rock shaft operatively connected with said valve and extending outwardly through said casing, a detent arm secured to said rock shaft, an operating lever secured to said detent arm, a detent lever pivotally secured at one end and adapted for co-action with said detent arm, a trip lever pivotally secured between its ends and adapted for co-action with said detent lever, and a trip rod secured to said scale and adapted to actuate said trip lever to cause actuation of said detent lever and disengagement thereof from said detent arm.

7. In a can-filling machine, the combination with a scale, of a casing having a liquid inlet and a liquid outlet, a valve normally closing said liquid outlet, a rock shaft journaled in one of the walls of said casing and extending inwardly and outwardly therefrom, an actuating lever secured at one end to said shaft within said casing and having connection with said valve, a detent arm secured to the other end of said shaft without said casing, an operating lever extending from said detent arm, a detent lever having a detent plate adapted to engage said detent arm, means for retaining said detent lever in elevated position and for regulating such position, a trip lever engaging said retaining means, and a trip rod secured to said scale and having its upper end in contact with said trip lever.

8. In a can-filling machine, detent mechanism comprising a pivoted depending arm having a shoe at its lower end, a detent lever pivotally secured at one end and having a portion engaging said shoe, a bolt passing through said detent lever, a spring exerting pressure against said detent lever, a trip lever against which one end of said bolt bears.

9. In a can-filling machine, the combination with a supporting member, of a detent arm pivotally secured at its upper end and having a shoe at its lower end, a detent lever secured at one end to said supporting member and having a part adapted to engage said shoe, a bolt passed adjustably through said detent lever, a spring secured to said support and exerting its force against said detent lever, and a trip lever against which said bolt bears.

10. In a can-filling machine, the combination of a bracket having spaced outstanding bosses at its lower end, a supporting member secured to said bosses and having an outstanding stop lug thereon, a detent arm pivotally secured at its upper end, a detent lever secured to said supporting member and to one of the bosses of said bracket and having a hub portion, a vertically-adjustable detent plate on said hub portion

- and a cylindrical lengthening rod passing through said plate and threaded into said hub portion, said plate being adapted to bite against the lower end of said detent 5 arm, a bolt passing adjustably through said detent lever, a spring secured to said supporting member and bearing with one end against the under side of said detent lever, a trip lever pivotally connected to said supporting member and having an outstanding stop lug whose under side is engaged by the upper end of said bolt, said trip lever being adapted to bear against the outstanding stop lug of said supporting member, and 10 means for actuating said trip lever and through the medium of said bolt and cause actuation of said detent lever to disengage said detent plate from said detent arm.
11. In a can-filling machine, the combination of a casing having a horizontal conduit and a vertical conduit at one end of said horizontal conduit extending both above and below the latter, a nozzle removably secured to the lower end of said vertical conduit, a valve adapted to fit into said nozzle and having a socket at its upper end, a stud loosely pinned within said socket and extending upwardly therefrom, said stud having its upper end threaded, a loop 15 into the lower end of which the threaded upper end of said stud is secured, a rod threaded into the upper end of said loop, a weight secured to the upper end of said rod, a rock shaft extending transversely therethrough the horizontal conduit at the other end thereof, and a valve actuating lever within said horizontal conduit secured at one end to said shaft and having a hook at its other end extending through said loop.
12. In a can-filling machine, the combination with a support, a bracket extending from said support and comprising two exact counterparts connected together, said counterparts having depressions at each end 20 forming openings through one of which said support is passed, and a combined valve and mechanism casing having a stud extending therefrom and entered into the other opening or said bracket.
13. In a can-filling machine, a bracket formed of two counterparts fastened together, each of the two counterparts having a semi-circular transverse depression at its inner side near each end thereof co-operating 25 with the semi-circular depression of the other of said two counterparts to form a circular opening at each end of the bracket, a scale having a member provided with a stud adapted to fit into one of said openings, and an upright having a cylindrical portion passed through the other of said circular openings, means for clamping one end of said bracket to said support, and means for 30 clamping the stud of said scale member into the opening at the other end of said bracket.
14. In a can-filling machine, a bracket formed of two counterparts fastened together, each of the two counterparts having a V-shaped depression at its inner side near one end thereof co-operating with the V-shaped depression of the other of said two counterparts to form a square opening at 35 each end of the bracket, a combined valve and mechanism casing provided with a square stud adapted to fit into one of said square openings, and an upright having a square portion passing through the other of said square openings, means for clamping one end of said bracket to said support, and means for clamping the stud of said casing into the opening at the other end of said bracket.
15. In a can-filling machine, the combination of a casing having valve controlling mechanism therein to govern the flow of liquid therethrough, detent mechanism connected to said valve controlling mechanism, automatic trip mechanism for releasing the detent mechanism and controlling mechanism including a hand operating lever extending from said detent mechanism and having a longitudinal slot therein, a stud adjustable in said slot, and a vertically-movable foot operated rod having a lifter thereon adapted for co-action with said stud.
16. In a can-filling machine, valve operating mechanism including a hand lever, a combined guide and stop member having an adjustable stop element thereon adapted to be engaged by said operating lever and a guide opening formed therethrough, and foot mechanism including a vertically-movable rod guided for movement in said guide opening.
17. The combination with a combined valve and mechanism casing having a shaft bearing extending therefrom, a rock shaft extending through said shaft bearing, a two-armed bracket secured to said shaft bearing, a detent arm secured to said rock shaft, an operating lever extending from said detent arm, a supporting member secured to both arms of said bracket and having a vertically-disposed portion provided with an outstanding stop lug and a horizontally-disposed portion, a detent lever secured to said supporting member and to one arm of said bracket and having a detent arm and an adjustable element extending upwardly therefrom near its outer end, a spring secured to the horizontally-disposed portion of said supporting member exerting pressure against said detent lever, and a trip lever secured to the vertically-disposed portion of said supporting member and engaging said outstanding stop lug with its upper face and engaged by the adjustable element of said detent lever at its under side.
18. In a can-filling machine, foot operating mechanism including a vertically-movable

- able rod, an actuator member on said rod comprising a body portion and an upwardly swinging spring-pressed trip dog having an inwardly and outwardly inclined surface 5 and a substantially flat horizontal surface, and a hand operating lever having a stud thereon in the path of said dog, said stud being substantially V-shaped in cross section, said dog being adapted to engage the under side of said stud when said operating 10 rod is elevated and to pass idly beneath said stud when said rod is lowered.
19. In a can-filling machine, the combination of a rock shaft, a detent arm on said rock shaft having a detent shoe at its lower end, and a detent lever pivotally secured and comprising a hub portion, a lengthening rod threaded into said hub portion, a detent plate adapted to engage said detent shoe 15 bearing against said hub portion and through which said lengthening rod is passed, a nut on said lengthening rod bearing against said detent shoe and a main portion extending outwardly from said lengthening rod into which said lengthening rod is 20 threaded.
20. In a can-filling machine, the combination with valve operating mechanism, of a detent arm secured to a part of said mechanism, a detent lever having a part thereof engaging said detent arm, a trip lever adjacent said detent lever adapted to actuate the latter, and means for regulating the extent of movement of said detent lever.
21. In a can-filling machine, the combination of a trip lever and a detent lever, one of said levers having a contact element adapted to engage the other and means for regulating the point of contact of said contact element with the lever in contact therewith.
22. In a can-filling machine, a detent lever pivotally secured at one end and having a contact point at its other end, a trip lever pivotally secured between its ends, and means embodied in the construction of one of said levers to lengthen or shorten the distance between the pivot thereof and said contact point.
23. In a can-filling machine, the combination with a support, of can filling mechanism carried by said support, a scale comprising a scale frame also carried by said support, a scale beam fulcrumed on said scale frame and having fulcrum members at its outer ends, a platform frame carried by the fulcrum at one end of said scale beam, a table support fulcrumed at the other end of said scale beam and having trip means adjustable thereon adapted to cause operation of said can filling mechanism to shut off the flow of liquid therefrom, a platform vertically adjustable on said platform frame, and a weight table on said table support.
24. In a can-filling machine, the combination of an upright having a bracket extending therefrom, a scale frame having a depending stud fastened into said bracket, a scale beam fulcrumed on said frame, a weight table at one end of said scale beam, 70 and a platform at the other end of said scale beam adapted to have cans or other receptacles to be filled placed thereon.
25. A can-filling machine comprising an upright, a bracket secured to said upright and extending therefrom, a liquid tank supported by said bracket, loops at opposite ends of said bracket, upright supports fastened into said loops, can filling mechanism carried by said upright, and a scale also carried by said upright.
26. A can-filling machine comprising an upright having a non-circular portion, a bracket secured to said upright and extending therefrom, a base to which said upright is secured, a liquid tank supported by said bracket, loops secured to opposite ends of said bracket, and supports secured to said base and extending upwardly through said loops and fastened therein.
27. In a can-filling machine, the combination of an upright, a bracket secured to said upright and extending therefrom, a scale frame secured centrally to said bracket, supporting rods having opposite ends of said scale frame secured thereto, a scale beam fulcrumed between its ends on said scale frame, a platform carried by one end of said scale beam, and a weight table carried by the other end thereof.
28. In a can filling machine, a scale having a scale frame provided with vertical openings at each end, a scale beam journaled between its ends on said scale frame, a platform frame carried by said scale beam at one end thereof, a rod extending downwardly therefrom through one of the vertical openings in said scale frame, a weight table at the other end of said scale beam, a rod extending downwardly therefrom through the other vertical opening of said scale beam, and a balance lever pivotally secured between its ends and having opposite ends secured to the lower end of said rods.
29. In a can-filling machine, an upright, a bracket extending from said upright, a scale frame having a depending stud centrally between its ends fastened into the outer end of said bracket and projecting beneath the same, a scale beam fulcrumed on said scale frame, a balance lever pivotally secured between its ends to the lower end of said stud, rods extending upwardly, a platform fulcrumed on one end of said scale beam and having one of said rods secured thereto, and a weight table fulcrumed on the other end of said scale beam and having the other rod secured thereto, said balance lever having opposite ends pivotally connected to the lower ends of said rods.

30. In a can-filling machine, the combination with an upright and a bracket secured thereto and extending therefrom, of a scale frame having a depending stud centrally between its ends fastened into said bracket, said scale frame comprising a longitudinal member and a transverse member midlength thereof and extending from opposite sides of said longitudinal member, said transverse member having upstanding lugs provided with V-shaped depressions in their upper faces, a scale beam having a central transverse member, end members and arms connecting said central transverse member and end members, a fulcrum member passed through said central transverse member having opposite ends provided with downwardly directed V-shaped portions fitting into the V-shaped depressions of said scale frame, a platform fulcrumed to one end of said scale beam, and a weight table at the other end thereof.
31. In a can-filling machine, the combination with an upright and a bracket secured thereto and extending therefrom, of a scale frame having a depending stud centrally between its ends fastened into said bracket, said scale frame comprising a longitudinal member and transverse member midlength and extending from opposite sides thereof, 30 said transverse member having upstanding lugs and hardened inserts in said lugs and being provided with V-shaped depressions in their upper faces extending into said hardened inserts, a scale beam having downwardly-directed V-shaped portions forming knife edges which rest in the extended portions of said depressions in the hardened inserts of the upstanding lugs on said scale frame, a platform at one end of said scale 40 beam, and a weight table at the other end thereof.
32. In a can-filling machine, a scale frame supported by a part thereof, a scale beam fulcrumed midlength on said scale frame, 45 a weight table at one end of said scale beam, a platform frame at the other end thereof comprising a hub portion and four diagonally-disposed arms extending outwardly from said hub portion and provided at their outer ends with vertical openings, rods adjustably secured in said platform frame, and a platform secured to the upper ends of said rods.

In testimony whereof I affix my signature.
JOSEPH C. BRUNO.
